UNITED STATES PATENT OFFICE

2,468,148

FREQUENCY CONTROL SYSTEM

George S. Wachtman, Harrisburg, Pa.

Application June 16, 1945, Serial No. 599,828

5 Claims. (Cl. 250—40)

1

My invention relates broadly to frequency control systems and more particularly to precision tuning circuits for frequency control systems.

One of the objects of my invention is to provide a construction of electrical tuning circuit for frequency control systems in which a high degree of precision in tuning adjustment may be secured with relatively inexpensive equipment.

Another object of my invention is to provide an electrical tuning circuit of high efficiency which may be adjusted with ease to selected frequencies within a band of frequencies with high precision.

Another object of my invention is to provide an oscillation system that can be closely calibrated and which will retain this calibration at any point through a specified frequency range.

Another object of my invention is to provide a compensation system for a control condenser in an oscillator circuit in which the bandspread or frequency range of the control condenser may be made equal at all frequencies to which the circuit may be tuned.

Other and further objects of my invention reside in the arrangement of electrical condensers in association with a tuning inductance as set forth more fully in the specification hereinafter following by reference to the accompanying drawings, in which:

Figure 1 schematically shows a bandspread circuit referred to hereinafter for explaining the operation of the circuit of my invention; Fig. 2 shows a modified bandspread circuit hereinafter referred to in explaining the theory of my invention; Fig. 3 illustrates a form of bandspread circuit that operates in a manner opposite to the theory of operation of the circuit of Fig. 2; Fig. 4 is a schematic view of a bandspread circuit which operates in a manner opposite to the theory of operation of the circuit of Fig. 2; Fig. 5 is a further schematic bandspread circuit which I refer to hereinafter in explaining the theory of my invention; Fig. 6 is a further schematic circuit diagram embodying certain of the features of my invention herein which combines the circuits of Figs. 2 and 3; Fig. 7 schematically shows a circuit embodying certain of the features of my invention and which combines the circuits of Figs. 2 and 6; Fig. 8 shows a circuit embodying certain of the features of my invention and which is a modified form of the circuit of Fig. 7; Fig. 9 illustrates a circuit arrangement embodying the principles of my invention and

2

which includes an oscillator system having compensating means for correcting for lack of uniformity of control range of the usual bandspread condenser; Fig. 10 shows a further form of compensation circuit embodying my invention; Fig. 11 combines the circuits of Figs. 8 and 10 in securing more effective compensation for the bandspread tuning condenser; Fig. 12 illustrates the circuit of my invention provided with adjustment means for correcting the bandspread control condenser at the minimum frequency to which the circuit is tunable; Fig. 13 schematically illustrates a circuit arrangement embodying my invention for providing compensation for the bandspread condenser at its maximum tunable frequency; Fig. 14 combines the desirable features of the circuits of Figs. 12 and 13 for providing greater ease of adjustment in effecting compensation of the bandspread tuning condenser; Fig. 15 shows an improved arrangement over that illustrated in Fig. 14 in which simultaneous operation of the control condensers in different parts of the circuit are effected; Fig. 16 shows a modification of the circuit arrangement of Fig. 15 including means which are adjustable to fix the minimum capacity and/or maximum frequency of the circuit; and Fig. 17 is a further modified form of the circuit shown in Fig. 16 for obtaining more stabilized and precision frequency control.

The improved circuit of my invention is adapted for use as a variable frequency oscillator, a signal generator, an exciter unit for a transmitter, a crystal calibrating and finishing oscillator, a beat frequency oscillator and a variable frequency low power transmitter. The circuit is also adapted for use as a Q meter; in the measurement of inductance, capacity and resistance at radio frequencies with an accuracy, for instance, of .01% at 4.5 megacycles to 9.0 megacycles with a bandspread of 100 kilocycles.

Fig. 1 of the drawings shows the simplest of all bandspread circuits in which tuning condenser 1 has bandspread condenser 2 connected in parallel therewith and connected to opposite terminals of inductance 3.

In Fig. 2 I have shown the bandspread condenser 2 connected to a tap 8 on inductance 3 at one side and to the terminal of the inductance 50 at the other side rather than directly in parallel with the tuning condenser 1 as in Fig. 1. The circuits of both Figs. 1 and 2 are of the "parallel tuned" type. The prime disadvantage in using either circuit shown in Fig. 1 or Fig. 2 lies in 55 the fact that the amount of bandspread or range

covered by bandspread condenser 2 varies in proportion to, although not a linear proportion, and in the same direction as the frequency, that is, it increases with an increase in resonant frequency of the whole circuit.

In my investigations of the circuits of Figs. 1 and 2 I discovered that when the bandspread condenser 2 is arranged in series with main tuning condenser 1, the action of the bandspread condenser 2 in the circuit of Fig. 3 is just the opposite of the action of bandspread condenser 2 in the arrangement shown in Fig. 1, that is, with an increase of resonant frequency of the whole circuit the range covered by bandspread condenser 2 in the circuit of Fig. 3 is inversely proportional to the frequency, and similarly to the action of bandspread condenser 2 in the circuits of Figs. 1 and 2, the proportion is not a linear one. The action of bandspread condenser 2 in the circuits of Figs. 1 and 2 is directly opposite to the action of bandspread condenser 2 in the circuits of Figs. 3 and 4. Insofar as the bandspread condenser 2 is concerned its action in either of the circuits of Figs. 3 and 4 is the mirror image of its action in the circuits of Figs. 1 and 2. The circuit of Fig. 3 illustrates the main tuning condenser 1 arranged in series with bandspread condenser 2. In Fig. 4 I have shown an arrangement wherein it is possible to obtain a finer control of frequency by means of bandspread condenser 2 by arranging a vernier or paddler condenser 4 in parallel therewith. The vernier or paddler condenser 4 connects between the point 9 common to the bandspread condenser 2 and main tuning condenser 1 and in circuit with inductance 3 as shown.

The circuits of Figs. 3 and 4 have the same disadvantages as those of Figs. 1 and 2, that is, the bandspread range varies with a variation of resonant frequency of the whole circuit.

I have verified all of the foregoing results experimentally and from these investigations I drew the conclusions that the bandspread range can be made to remain reasonably constant regardless of the setting of main condenser 1 or the resonant frequency of the circuit. Accordingly I arrange the circuit as shown in Fig. 5 in which condenser 2a has the same action as condenser 2 of Fig. 3 and condenser 2b has the same action as condenser 2 of Fig. 1. By ganging the rotors or movable elements of condensers 2a and 2b in Fig. 5 I obtained simultaneous control of their respective characteristics. It is apparent from a study of the circuit of Fig. 5 that one of the elements of the bandspread condenser 2a is connected to the same point on the inductance 3 as one of the elements of the bandspread condenser 2b. This fact occasioned me to further reason that as it was necessary to gang the rotors of condensers 2a and 2b to obtain simultaneous control, it should be possible to utilize a single condenser having two stationary elements and one rotating or movable element or in other words a split-stator or dual condenser. This I did as shown in Fig. 1 of my copending application for Letters Patent Serial No. 505,048, filed October 5, 1943, now Patent No. 2,400,895, granted May 28, 1946. Further study and research has resulted in the development of the circuits herein depicted in Figs. 6-17.

Referring to Fig. 6 the functions of condenser 2 of Fig. 2 and condenser 2 of Fig. 3 have been combined in one condenser 10 in Fig. 6 which has but one rotor and one stator. This is made possible by the tap 8 on the inductance 3, which

must be placed just right to obtain equal bandspread at either end of the tuning range of condenser 1. The condenser 1 connects across a portion of the inductance 3 between tap 8 and one end of the inductance while condenser 10 connects with condenser 1 as at 9 and across another portion of inductance 3 between tap 8 and the other end of the inductance 3.

Fig. 7 is the result of the combination of the circuits of Figs. 2 and 4. In Fig. 7 the function of condenser 2 in Fig. 2 and the function of condenser 2 in Fig. 4 have been combined in a single condenser 11 which has but one rotor and one stator. As in Fig. 6 the tap 8 on the inductance 3 must be placed properly and in addition the paddler condenser 4 must have the proper capacity to enable the bandspread condenser 11 to have the same range of control at either end of the tuning range of the condenser 1. Condenser 1 is connected in effect across one portion of inductance 3 between tap 8 and one end of inductance 3. Condensers 4 and 11 are in effect connected in parallel and connected at one end with condenser 1 as at 9 and across another portion of inductance 3, that is, between the tap 8 and the other end of inductance 3.

Fig. 8 is a variation of Fig. 7 wherein the control range of condenser 11 may be varied by adjusting the condenser 12. Condenser 1 is in effect connected across one portion of inductance 3, that is, between tap 8 and one end of inductance 3. Condensers 11 and 12 are in effect connected in series and the combination connected in parallel with condenser 4. The combination thus formed is connected at one end with condenser 1 as at 9 and is connected across another portion of inductance 3, that is, between tap 8 and the other end of inductance 3.

The circuits of Figs. 5 and 6 have a serious but correctible fault which is that as the frequency is varied from the minimum to the maximum, or vice versa, attainable with any particular set of components the range of control exerted by the combined and simultaneous action of condensers 2a and 2b and/or the condenser 10 varies slightly, being a minimum at mid frequency and a maximum at the minimum or maximum frequency points. This defect is serious if accurate work is to be done with the circuit and may be corrected by the inclusion of one or more condensers which may be adjusted either separately or automatically in unison with a variation or rotation of condenser 1.

A slight variation of condenser 4 in Fig. 7 or variation of either one or both of the condensers 4 and 12 of Fig. 8 can be made to compensate for the lack of uniformity of the control range of condenser 11 in either circuit. The lack of uniformity of the control range of the bandspread condenser 11 is common to all of the circuits shown if no means were provided to compensate for this defect or if the means were provided but not used.

Fig. 9 is a diagram of a circuit in which such a means has been provided in the form of condenser 14. Condenser 1 is in effect connected across one portion of inductance 3 between tap 8 and one end of inductance 3. Condensers 4, 11 and 14 are in effect connected in parallel and connected at one side with condenser 1 as at 9. The combination thus formed is connected across another portion of inductance 3 between tap 8 and the other end of inductance 3.

In Fig. 10 which is an elaboration of the circuit of Fig. 9 the condenser 15 has been inserted

to provide a means of adjusting the amount of compensation provided by the condenser 14. Condenser 1 is in effect connected across one portion of inductance 3 between tap 8 and one end of the inductance 3. Condensers 14 and 15 are in effect connected in series. The series combination is in effect connected in parallel with condensers 4 and 11. This combination is connected at one side with one side of condenser 1 as at 9. The circuit thus formed by condensers 4, 11, 14 and 15 is connected in parallel with another portion of inductance 3, that is, between tap 8 and the other end of inductance 3.

Fig. 11 is a combination of Figs. 8 and 10 in which the condenser 12 is the bandspread range adjustment and the condenser 15 is the compensation adjusting means. As it is necessary that the condenser 4 and the tap 8 be adjusted with respect to each other in such a way that the control range of condenser 11 is equal at both the minimum and maximum frequencies to which the circuit is tunable, it was also necessary to find a practicable means of doing so. Condensers 14 and 15 are in effect connected in series. Condensers 11 and 12 are also in effect connected in series. Both of these series paths are connected in parallel and are connected in parallel with condenser 4. The combination thus established is connected at one side with condenser 1 as at 9. The combination is also connected in parallel with another portion of inductance 3 between tap 8 and the other end of inductance 3.

The circuits of Figs. 12-14 are variations of the circuit of Fig. 10, the difference being that the condensers 16 and 17 have been inserted to allow the bandspread or frequency range of condenser 11 to be adjusted so that it is equal at the minimum and maximum tunable frequencies of the whole circuit. The circuit of Fig. 12 allows adjustment of the control range of condenser 11 by means of condenser 16 at the minimum frequency to which the circuit is tunable while the circuit of Fig. 13 allows adjustment of the control range of condenser 11 at its maximum tunable frequency by means of condenser 17. The circuit of Fig. 14 is a combination of the circuits of Figs. 12 and 13 embodying all of their characteristics plus a greater ease of adjustment.

In Fig. 14 the inductance for the system is illustrated at 3 connected to main tuning condenser 1, in series with the vernier or padder or minimum frequency adjustment condenser 4. Thus a series path is provided through inductance 3, main condenser 1 and the padder condenser 4. A tap 8 on inductance 3 connects through the pair of adjustable trimmer condensers 16 and 17 to the mid-tap 9 between main condenser 1 and padder condenser 4. Two electrical paths are provided between points in the circuit 16-17 and a point between adjustable vernier or padder condenser 4 and the terminal of inductance 3. One of these paths includes the variable condenser 11 and the other path includes variable condensers 14-15.

In adjusting the circuit main condenser 1 is set in a maximum capacity position. Condensers 16 and 17 are set at approximately half capacity positions. Condenser 11 and condensers 14-15 are set at approximately maximum capacity positions. The procedure then contemplates the adjustment of condenser 4 to render the circuit responsive to a predetermined minimum frequency. With main condenser 1 set at maximum

capacity position, condenser 16 is then adjusted so that condenser 11 has the proper frequency coverage between its minimum and maximum capacity. Condenser 17 is then adjusted so that condenser 11 has the same coverage at the high end of the spectrum as it did at the lower end of the spectrum under control of the adjustable condenser 16. Condenser 14 is then adjusted to minimum capacity position and condenser 1 is adjusted so that the circuit is responsive to a frequency mid-way between its maximum and minimum frequency. Condenser 11 is then adjusted from minimum to maximum capacity to determine if it has the same frequency coverage as it had at the maximum or minimum frequencies of the circuit. If condenser 14 can be set at any point between one-half maximum capacity and minimum capacity so that condenser 11 has this coverage, the circuit can be considered as adjusted and the dials on the various condensers correspondingly calibrated.

The circuit of Fig. 15 is identical to the circuit of Fig. 14 with the exception that condenser 1 has been mechanically connected to condenser 16 by means of linkage 18 so that the compensation condenser 14 may be simultaneously and automatically adjusted with the main tuning condenser 1.

Fig. 16 depicts a circuit embodying the characteristics of Fig. 15 plus the condenser 19, which is adjustable to set the minimum capacity and/or the maximum frequency of the circuit. The condenser 19 may also represent the minimum capacity of the circuit, i. e., the stray capacities always present in any circuit. In Fig. 16 the circuit elements described in connection with Fig. 14 are all arranged as heretofore explained and in addition main condenser 1 and variable condenser 14 are interconnected as represented at 18 for simultaneous adjustment. Also the additional condenser 15 in series with the path containing condenser 14 more effectively adjusts the compensation capacity path through condenser 14. Condensers 1 and 14 are initially adjusted as described in connection with Fig. 14 and thereafter simultaneously controlled through the cascade control represented at 18. The tap 8 on inductance 3 may be made adjustable in the several circuits hereinbefore described.

The circuit of Fig. 17 is a variation of the circuit of Fig. 16 wherein the tap 8 on the inductance 3 has been omitted and a small inductance 20 added. This inductance 20 is coupled to the inductance 3 in such a manner that the net effect of said inductance 20 is the same as if the tap 8 were used instead, as in the other figures. The inductance 20 may be either fixed or adjustably coupled to inductance 3, in the latter case the effect is the same as if tap 8 were adjustable in the other figures. If inductance 20 is adjustable, it is possible to omit condenser 17.

It is apparent that the Figs. 15, 16 and 17 are refinements of the circuit of Fig. 14, but these same refinements may be applied to any of the other circuit of any of the other figures.

If compensation is used all of the circuits from Fig. 7 to and including Fig. 17 may be adjusted to obtain the same net results provided the proper components are chosen in each case.

The values of the components of a typical oscillation circuit such as in Figs. 14 or 16 are:

1=325 micro-micro-farad variable condenser.
11 and 14=100 micro-micro-farad variable condenser.

- 3=Inductance 8.7 micro-henries tapped one-third number of turns from end of coil to which 4, 11 and 14 are connected.
 4=100 micro-micro-farad adjustable vernier or paddar condenser.
 15, 16, 17 and 19=3-30 micro-micro-farad trimmer condensers.

The circuit arrangements of my invention have been found very practical in construction and production and economical in the use of equipment. Variable condensers of customary construction may be employed in the circuits of my invention herein and it is unnecessary to utilize any special form of "dual condenser" which inherently involves an insulation problem requiring substantial electrical insulation between the adjustable member and one end of the tuning inductance. Approximately 10% may be saved on parts costs in the circuit arrangements shown in Figs. 6-17 over that possible in circuits which employ a "dual condenser."

The oscillation control circuits of my invention are intended to be connected to the input and/or output systems of electron tube circuits for sustaining the oscillations developed in the tunable circuits at substantially constant frequency.

Automatic compensation may be accomplished in all of the circuits of my invention from Fig. 7 to Fig. 17 inclusive by simultaneous control of condensers 1 and 4 or 1 and 14. The minimum capacity setting condenser 19 may be included in any of the circuits and depending on the criticalness of its setting may be incorporated in shunt with any portion of the whole of inductance 3. The inductance 20 of Fig. 17 may be utilized in any of the circuits. The circuits of Figs. 7 to 17 inclusive are each individually important, as each with properly proportioned components may be utilized with considerable effectiveness.

While I have described my invention in certain of its preferred embodiments, I realize that modifications may be made and I desire that it be understood that I intend no limitations upon my invention except as may be imposed by the following claims.

What I claim and desire to secure by Letters Patent of the United States is as follows:

1. An oscillation control circuit comprising an inductance, a main tuning condenser, a vernier condenser, a series path electrically connected to include said main condenser and said vernier condenser across said inductance, a tap intermediate said main condenser and said vernier condenser, a coupling inductance coupled to the aforesaid inductance and electrically connected to that portion of the inductance which connects to the series path that includes said main condenser and said vernier condenser and a circuit connection extending from the other end of said coupling inductance to said tap intermediate said main condenser and vernier condenser.

2. An oscillation control circuit comprising an inductance, a main tuning condenser, a vernier condenser, a series path electrically connected to include said main condenser and said vernier condenser across said inductance, a tap intermediate said main condenser and said vernier condenser, a coupling inductance coupled to the aforesaid inductance and electrically connected to that portion of the inductance which connects to the series path that includes said main condenser and said vernier condenser, a circuit connection extending from the other end of said coupling inductance to said tap intermediate said main condenser and said vernier condenser and

tuning means connected between said circuit connection and one side of the series path which connects between said main condenser, said vernier condenser and said first mentioned inductance.

3. An oscillation control circuit comprising an inductance, a main tuning condenser, a vernier condenser, a series path electrically connected to include said main condenser and said vernier condenser across said inductance, a tap intermediate said main condenser and said vernier condenser, a coupling inductance coupled to the aforesaid inductance and electrically connected to that portion of the inductance which connects to the series path that includes said main condenser and said vernier condenser, a circuit connection extending from the other end of said coupling inductance to said tap intermediate said main condenser and said vernier condenser, tuning means connected between said circuit connection and one side of the series path which connects between said main condenser, said vernier condenser and said first mentioned inductance, band spread tuning means connected between said circuit connection and the last mentioned portion of said inductance in parallel with said tuning means, and means for simultaneously adjusting said tuning means and said main tuning condenser.

30 4. An oscillation control circuit comprising an inductance, a main tuning condenser, a vernier condenser, a series path electrically connected to include said main condenser and said vernier condenser across said inductance, a tap intermediate said main condenser and said vernier condenser, a coupling inductance coupled to the aforesaid inductance and electrically connected to that portion of the inductance which connects to the series path that includes said main condenser and said vernier condenser, a circuit connection extending from the other end of said coupling inductance to said tap intermediate said main condenser and said vernier condenser, tuning means connected between said circuit connection and one side of the series path which connects between said main condenser, said vernier condenser and said first mentioned inductance, and a condenser disposed in said circuit connection on each side of the point of connection 50 of said tuning means thereto, one of said last mentioned condensers being connected with said coupling inductance and the other of said last mentioned condensers being connected to the tap intermediate said main tuning condenser and said vernier condenser.

55 5. An oscillation control circuit comprising an inductance, a main tuning condenser, a vernier condenser, a series path electrically connected to include said main condenser and said vernier condenser across said inductance, a tap intermediate said main condenser and said vernier condenser, a coupling inductance coupled to the aforesaid inductance and electrically connected to that portion of the inductance which connects to the series path that includes said main condenser and said vernier condenser, a circuit connection extending from the other end of said coupling inductance to said tap intermediate said main condenser and said vernier condenser, tuning means connected between said circuit connection and one side of the series path which connects between said main condenser, said vernier condenser and said first mentioned inductance, a condenser disposed in said circuit connection on each side of the point of connection of said tuning

means thereto, one of said last mentioned condensers being connected with said coupling inductance and the other of said last mentioned condensers being connected to the tap intermediate said main tuning condenser and said vernier condenser, band spread tuning means connected between said circuit connection and the common ends of said inductances and means for simultaneously adjusting said tuning means and said main tuning condenser.

GEORGE S. WACHTMAN.
